[57] **CLAIM**

The ornamental design for a combined leg support and ash catcher for outdoor cooker, as shown and described.

DESCRIPTION

FIG. 1 is a perspective view of a combined leg support and ash catcher for outdoor cooker showing our new design;

FIG. 2 is a rear elevation view thereof; and,

FIG. 3 is a bottom plan view thereof.

The grill in broken lines is shown for illustrative purposes only and forms no part of the claimed design.

FIG. 1

FIG. 2

FIG. 3
